UNITED STATES PATENT OFFICE.

BERTHOLD GMÜR, OF SCHÄNIS, AND OTTO FLATZ, OF NIEDERURNEN, SWITZERLAND, ASSIGNORS OF ONE-HALF TO BRONISLAV DEISENBERG, OF TRAVNIK, BOSNIA, AND JOSEPH GMÜR, OF SCHÄNIS, SWITZERLAND.

DYNAMO FOR TELEGRAPHIC PURPOSES.

SPECIFICATION forming part of Letters Patent No. 396,557, dated January 22, 1889.

Application filed June 9, 1888. Serial No. 276,564. (No model.)

To all whom it may concern:

Be it known that we, BERTHOLD GMÜR, a citizen of the Republic of Switzerland, residing at Schänis, in the Republic of Switzerland, 5 and OTTO FLATZ, a subject of the Emperor of Austria, residing at Niederurnen, in the Republic of Switzerland, have invented certain new and useful Improvements in Generating Electric Currents for Telegraphic and Telephonic Purposes, (which has not been patented to ourselves or to others with our knowledge or consent in any country,) of which the following is a specification.

Our invention consists in the combination 15 of a dynamo or magneto electric machine especially designed and wound for this purpose with a weight motor provided with a hoisting mechanism. The telegraph-operator is enabled by this contrivance to effect a constant traction on the dynamo or magneto electric machine by his personal labor and without being hindered in his other duties, and he can by these means generate an inexpensive, steady, and always ready current 20 for telegraphic and telephonic purposes instead of by using galvanic batteries.

The resistance of the shunt-coils which are wound on the field-magnet of the dynamo-electric machine is about one-third to one-fifteenth as much as the resistance of the outside circuit formed by the receiving apparatus (sounders, registers, relays, &c.) and the telegraph-lines. In consequence the electrical energy needed by the outside circuit 30 will be only a small portion of the whole mechanical work which the dynamo-electric machine has to transmit into electrical energy. In consequence of this proportion of resistance of dynamo-shunt and the outside circuit the intensity of the current in the armature-wire is nearly independent from switching the outside circuit on or off by the telegraph-key. Therefore the mechanical work obtained from the weight-motor being always 35 nearly the same, the outside circuit being switched on or off, and as the traction of the weight on the armature of the dynamo due to the construction of the motor being necessarily always the same, a state of equilibrium

results, whereby the armature speed of the 50 dynamo will be constant, as well as its electro-motive force.

By switching with a special switch the two shunt-coils of the field-magnet in multiple 55 arc or in series it becomes easy to change the electro-motive force of the dynamo nearly instantly according to the resistance of the telegraph-circuit—that is to say, to get in this way currents for local or line circuits. Besides this, the electro-motive force of the current-generator may be changed by altering 60 the working weight of the motor. Every case produces a new state of equilibrium answering to a given steady tension at the poles of the dynamo. The apparatus having, therefore, 65 in consequence of its construction a steady speed of armature, needs no special speed-regulator and no extra resistance-coils for the outside circuit. In consequence of the relatively high resistance of the field-magnet 70 coils and their relatively small magnetizing-power in comparison with other shunt-dynamos, and in proportion to the electro-motive force of this dynamo, (for instance, the electro-motive force of this dynamo being 75 about forty volts, the resistance of the shunt-circuit formed by the field-magnet coils will be about five hundred ohms,) the most part of the horseshoe of the field-magnet is made of cast-iron, so as to always have sufficient 80 remnant of magnetism, that the apparatus may give current immediately and show in a few seconds the proper speed and electro-motive force.

By the combination of our special weight- 85 motor with the current-generator the rotation of the armature in always the same direction is secured, and by further details of construction, set forth in the description hereinafter, the security of and ease in working the apparatus is guaranteed by the possibility of 90 immediately starting or stopping it.

In the accompanying drawings, which form part of this specification, Figure 1 represents a sectional side elevation of the apparatus. 95 Fig. 2 represents an end elevation, partly in section. Fig. 3 is a plan view of the apparatus. Fig. 4 is a detail section along the shaft

of the ratchet-wheels. Fig. 5 is a detail view of the brake mechanism. Fig. 6 is a vertical section of the switch on the line $c c$, Fig. 7; and Fig. 7 is a plan view of part of the dynamo and switch.

A cast-iron or other frame, a , is placed over the cut-out top of a table, t , or other suitable support. The shafts b c d of the dented wheels b' , b^2 , and b^3 are journaled in suitable 10 bearings in the frame a . The wheel b' gears into a pinion, c' , on the armature-shaft of the dynamo, the wheel b^2 gears into a pinion, c^2 , on the shaft b , and the wheel b^3 gears into a pinion, c^3 , on the shaft c . A chain-wheel, k , is 15 fastened on the shaft d of the dented wheel b^3 .

The shaft e supports most of the hoisting mechanism, as follows: Fastened on the shaft e is a chain-wheel, k' , and also two ratchet-wheels, z' and z^2 , preferably on opposite sides 20 of the chain-wheel k' . Hung loosely on this shaft e is a hoisting-pulley, r , which is secured against lateral displacement by a steady ring, r^3 , on one side, and the ratchet-wheel z^2 on the other side.

x' and x^2 are two clicks, which are in gear 25 in the teeth of the ratchet-wheels z' and z^2 , respectively. The pivot of the click x' , which is in gear with the ratchet-wheel z' , is fastened to the frame a , (see Fig. 4,) and the pivot 30 of the click x^2 is fastened to the pulley r . The click x^2 is pressed against the teeth of the ratchet-wheel z^2 by a spring, x^3 , secured to the pulley r .

The mechanism b' b^2 b^3 , &c., is put in motion 35 by a weight, f , preferably consisting of several removable plates. The weight f hangs by the pulley r^4 , carried thereby in a loop of the endless chain m , which chain is laid over the chain-wheel k and over pulleys r^1 r^2 , and 40 hung in the frame over a pulley, r^3 , carried by a weight, f' , over the chain-wheel k' on the shaft e and over the pulley r^4 . The chain is kept straight by the small counter-weight f' , that carries the pulley r^3 .

n is a chain that serves for hoisting the weight f . Said chain is connected at one end 45 to the pedal l . It passes thence over the leading pulley r^5 , hung in the frame and over the hoisting-pulley r , to which it is fastened. It 50 then proceeds to a spring, s , to which at n' the other end of the chain is connected. The opposite end of the spring s is linked in a fixture, n^2 , joining the table-legs. A stop, a^4 , limits the upward movement of the weight f . 55 The iron frame a also supports the current-generator.

In the foregoing description and accompanying drawings it is shown how the effect of the weight-motor is conveyed to the armature 60 of the dynamo by means of toothed wheels. If preferred, the transmission of the effect of the weight-motor to the dynamo may be made by means of pulleys and belts, or by friction-wheels, in place of the toothed wheels.

65 The current-generator is a so-called "shunt-dynamo" with a drum-armature. The iron cores E of the field-magnet are wound with

shunt-coils E' and the pillow-block A is screwed on the cast-iron bed-plate G of the dynamo. The bed-plate therefore joins both 70 magnet-cores and completes the magnetical horseshoe. A bearing, B , is cast in the bed-plate. The shaft c^6 of the armature lies in the bearings A and B and the armature is almost completely inclosed by the pole-pieces 75 of the field-magnet. The pins of the brush-holders are fixed and isolated on a frame, C , which is movable around the shaft of the armature. The brush-frame is pressed to a disk cast to the bearing B by two flat springs, 80 V . The brushes D may be pressed to the collector in any suitable well-known manner. Two wires or cables, d^4 , join the brush-pins with two contact-pieces of the switcher U .

The brushes preferably consist each of two 85 cylindrical bundles of thin copper wires held together by a German-silver binding-piece. On the free end of the armature or drum shaft c^6 , outside the pillow-block A , are fixed the pinion c' and a brake-disk, B' . The current-switcher U is screwed on the pole-pieces of the field-magnet E and consists of four contact-pieces, 1 2 3 4, fixed on a little board. Said contact-pieces are adapted to be joined 90 by a movable cross or switch, F , consisting of two copper or other bars, F' and F^2 , isolated from each other by the insulator F^3 , which cross or switch F makes contacts with 1, 2, 3, and 4 by its own elasticity. One of the bars 95 of the switch F is provided with a handle, f^4 . The contact-pieces 1 and 3 are connected with the cables d^4 , coming from the brush-holders, and also with wires d^6 d^6 , coming from the outside circuit—namely, the one from the ground 100 and the other from the telegraph-line. 105

The two inner terminals of the shunt-coils of the field-magnet are joined to the contact-pieces 1 and 3, while the other terminals of these shunt-coils are joined to the contact-pieces 2 and 4. When the handle f^4 of the cross or switch lever F is moved to the left, 110 it makes contact between the pieces 2 and 4, whereby the shunt-coils of the field-magnet are switched in series. If the cross-lever F is moved to the right, the contact-pieces 1 and 4 115 will be joined as well as 2 and 3, and so the shunt-coils of the field-magnet will be switched in multiple arc. If the lever stands in the central position, as shown in the drawings, the two ends of the outside circuit will be 120 joined directly and the coils of the dynamo-machine switched off from the outside circuit, and therefore protected against lightning.

The brake is constructed as follows: A small iron bar, N' , that lies in a bearing in 125 the cast-iron bed-plate G of the dynamo-machine, is provided with a handle, L , at one end, and at its other end with an elastic tongue, N . On the iron bar N' is a pin, y , which limits the turning of said bar to an angle of, 130 say, ninety degrees. The elastic tongue N is so applied that by turning the brake off it conveys to the armature a turning motion in the direction of rotation, resulting also

from the downgoing weight of the motor. Consequently a backward turning of the collector, which would set the brush-wires out of order, cannot take place.

5 The table t may be made separable, thereby presenting advantages to the apparatus for military telegraphic purposes. The stability of the table may be guaranteed by a joining iron bar, q , which serves also as an axis to the 10 pedal l of the hoisting mechanism.

If the apparatus is to be put in use for a telegraphic correspondence, the operator disengages the brake by turning the lever L to the left, and therewith conveys a powerful 15 turning motion to the armature in the direction of the weight-traction. The effect of the weight-motor produces the normal speed needed by the current-generator shaft c^6 in a few seconds. If the normal speed is wanted

20 in even less time, it suffices to increase the pressure on the pedal, whereby the weight-pulley r^4 is stopped in its upgoing course by the stop a^4 and an accelerated rotation on the armature is effected. As soon as the dynamo 25 has reached its normal velocity, the electrical current is ready for use for correspondence. At certain intervals the big weight must be lifted by pressure on the pedal. The downward motion of the pedal l gives to the pulley r a turning motion to the right. The ratchet-wheels z^1 and z^2 and the chain-wheel k' being fastened on the shaft e , and the click x^2 , being in gear with the ratchet-wheel z^2 , the shaft e , carrying the chain-wheel k' , must follow the turning motion of the pulley r to the right, whereby the weight f is lifted. At the raising of the foot and the return of the pedal effected by the spring s drawing on the chain n the pulley r and the click x^2 come back to 30 their former places. The click x' , fastened to the frame a , prevents the return of the two ratchet-wheels and the chain-wheel k' . When the correspondence is ended, the brake-lever is to be turned to the right, the brake-disk 35 enters between the elastic tongue N of the brake, and the whole mechanism is stopped by friction.

If a high electro-motive force for a line-circuit is wanted from the dynamo, the lever F 40 of the switcher U should be turned to the left, whereby the magnetizing-shunt of the dynamo is formed by the two coils of the field-magnet switched in series. If a low electro-motive force is wanted to act between relay 45 and sounder or register, the switcher F must be turned to the right, whereby the two coils E' of the field-magnet are switched in multiple arc, giving a shunt of one-fourth the resistance in the former case. Immediately the 50 speed of the mechanism will be brought down and the current-generator will give the desired electro-motive force for the local circuit.

During thunder-storms the switch-lever F must stand in the middle. The dynamo is 55 then switched off from the outside circuit. If the operator wants for his correspondence a higher or lower electro-motive force, this

can also be effected by increasing or decreasing the working-weight f , which change of weight can be made quite easily. 70

In using a magneto-electric machine in combination with this weight-motor the most part of the armature-current is to be consumed in a steady or changeable resistance base of about one-third to one-fifteenth as much resistance as that of the respective outside circuit. The poles of the resistance-coil should be in contact with the poles of the magneto-electric machine. There results by the above arrangement of using magneto-electric machines in combination with our weight-motor a state of equilibrium with constant speed and constant electro-motive force which is independent from switching the outside circuit on or off, as has been described for dynamo- 85 electrical machines.

The new practical effects and advantages of our invention consist—

First. In the possibility of using dynamo-electric currents for telegraphic and telephonic purposes, so that the galvanic batteries now in use can be dispensed with for large and small stations without need of other power than the small physical effort of the telegraph-operator. This is attained by our 90 peculiar construction of the dynamo in combination with the described weight-motor, wherewith an ever and everywhere ready and inexpensive electric source for all telegraphic work is given. 100

Second. In the possibility of using this electrical source for all respective distances for line-circuits, and also for local circuits, having only, when adjusting the apparatus for another distance, to turn the dynamo-switcher or to change the amount of the driving-weight, there being no need of putting any extra resistances in the outside circuit. 105

Third. In always having the same current in the outside circuit, resulting from the constant electrical tension at the poles of the dynamo or magneto electric machine, and for this reason the injurious and time-consuming adjustments of the receiving apparatus are overcome. 110

Fourth. In the very small amount of space needed for the whole apparatus.

Fifth. In the simplicity of all the details of the apparatus, which apparatus possesses at the same time the necessary stability, being easily transported, worked, and stopped. 120

Having now described our invention, what we claim is—

1. A weight-motor consisting of a train of gearing containing a chain-wheel, k , an endless chain, m , having two loops, one of said loops engaging the wheel k , a weight, f , carrying a roller, r^4 , that is placed in one of the loops of the chain m , and chain-wheel k' , for the chain m , ratchet z^2 , rigid with said wheel k' , and pulley r , having a pawl, x^2 , to engage the ratchet-wheel z^2 , and a treadle, l , connected by a chain, n , to the pulley r , combined with a dynamo or magneto electric machine, 130

all arranged and operating substantially as herein shown and described.

2. A weight-motor consisting of a train of gearing containing a chain-wheel, k ; an endless chain, m , having two loops, one of said loops engaging the wheel k ; a weight, f , carrying a roller, r^1 , that is placed in one of the loops of the chain m , and chain-wheel k' , for the chain m , ratchet z^2 , rigid with said wheel k' , and pulley r , having a pawl, x^2 , to engage the ratchet-wheel z^2 , and a treadle, l , connected by a chain, n , to the pulley r , combined with a dynamo-electric machine provided with a field-magnet made of a metallic conductor for retaining magnetism, said field-magnet being wound with shunt-coils of high resistance and magnetized with small current-power, whereby the dynamo will give quick and certain currents with the speed obtained from said weight-motor, substantially as described.
3. A weight-motor consisting of a train of gearing containing a chain-wheel, k ; an endless chain, m , having two loops, one of said loops engaging the wheel k ; a weight, f , carrying a roller, r^1 , that is placed in one of the loops of the chain m , and chain-wheel k' , for the chain m , ratchet z^2 , rigid with said wheel k' , and pulley r , having a pawl, x^2 , to engage the ratchet-wheel z^2 , and a treadle, l , connected by a chain, n , to the pulley r , combined with a dynamo-electric machine having a field-magnet consisting of a cast-iron bed-plate, two iron cores secured to said bed-plate, said cores being wound with shunt-coils of high resistance that are magnetized with small current-power, all arranged and operating substantially as herein shown and described.
4. A weight-motor consisting of a train of gearing containing a chain-wheel, k ; an endless chain, m , having two loops, one of said

loops engaging the wheel k ; a weight, f , carrying a roller, r^1 , that is placed in one of the loops of the chain m , and chain-wheel k' , for the chain m , ratchet z^2 , rigid with said wheel k' , and pulley r , having a pawl, x^2 , to engage the ratchet-wheel z^2 , and a treadle, l , connected by a chain, n , to the pulley r , combined with a dynamo-electric machine having a field-magnet that is wound with shunt-coils of about one-third to one-fifteenth as much resistance as that of the respective outside circuit, substantially as herein shown and described.

5. In a dynamo-machine, the cores E , having shunt-coils $E'E'$, combined with the switch U , having contact-pieces 1, 2, 3, and 4, that are connected to the shunt-coils and brushes, as described, and with the cross-switch F , that is adapted to engage two or more of the contact-pieces 1 2 3 4 at a time, whereby the field-magnet may be switched into series or multiple arc, and whereby the coils of the dynamo may be cut off from the outside circuit to protect the dynamo from lightning, substantially as described.

6. In a dynamo or magneto electrical machine for telegraphic or telephonic purposes, the armature-shaft c^6 and the disk B' , carried by said shaft, combined with the brake consisting of the bar N' , handle L , and elastic tongue N , all arranged substantially as herein shown and described.

In testimony whereof we have signed this specification in the presence of two subscribing witnesses.
